Primary Examiner — Kevin K Rudzinski*Assistant Examiner* — Richard Kearney(74) *Attorney, Agent, or Firm* — Alan D. Kamrath; Mayer & Williams PC(57) **CLAIM**

The ornamental design for a chain for a slide fastener, as shown and described.

DESCRIPTION

FIG. 1 is a perspective view of a chain for a slide fastener showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

7 is a bottom plan view thereof; and,

FIG. 8 is another perspective view thereof.
